HIGH-FREQUENCY-OSCILLATION
GENERATOR OR AMPLIFIER

Edward U. Condon, Edgewood, Pa., assignor to
Westinghouse Electric Corporation, East Pitts-
burgh, Pa., a corporation of Pennsylvania

Application March 14, 1940, Serial No. 323,912

10 Claims. (Cl. 315—6)

My invention relates to electrical oscillators, and has particular relation to apparatus for generating oscillations having a wave length of the order of decimeters.

It is an object of my invention to provide a decimeter-wave length oscillator of simple structure.

Another object of my invention is to provide a decimeter wave length oscillator capable of delivering substantial power.

An incidental object of my invention is to provide a hollow body electrical resonator, particularly adapted for use in an oscillator according to my invention.

More generally stated, it is an object of my invention to provide an oscillation generator capable of delivering substantial power and peculiarly suited for the purpose of supplying radiation having a wave length less than one meter.

According to my invention, a periodic lateral movement is impressed on a stream of electrical charges by the electric field of a hollow body resonator. As the stream vibrates laterally, it traces a path backward and forward across a periodic electromagnetic field, the instantaneous spacial distribution of which is such as to oppose the longitudinal movement of the charges. Energy is thus derived from the stream and may be radiated from a suitable antenna.

The novel features that I consider characteristic of my invention are set forth with particularity in the appended claims. The invention itself, however, both as to its organization and its method of operation, together with additional objects and advantages thereof, will best be understood by referring to the following description taken in connection with the accompanying drawing, in which the single figure is a diagrammatic view illustrating a preferred embodiment of my invention.

The apparatus shown in the drawing comprises a vacuum-tight container in the form of an elongated ellipsoid of revolution tempered of a metal such as copper or stainless steel or an insulator such as glass or a ceramic substance. If the container is composed of insulating material, a conducting layer should preferably be deposited on its inner surface. The container is in the preferred practice of my invention highly evacuated, although it may contain an inert gas or mercury vapor at a pressure of several microns to several millimeters of mercury.

An electron emissive filament 3 is suitably mounted at one end of the container 1. The

5 filament is partially enclosed within a dish-shaped metallic shell 5 having a small opening 7 in its base. The shell 5 is preferably grounded and a high negative potential 9 (shown symbolically as a battery) is impressed between the filament 3 and ground. The electrons emitted from the filament 3 are accelerated by the potential difference between the shell 5 and the filament, and concentrated into a narrow beam as

10 they pass through the opening 7. To avoid unnecessarily complicating the explanation, I have shown and described only the filament and the accelerating shell. In the construction of oscillators in accordance with my invention, additional 15 electrodes such as are common in the cathode-ray tube art will be found to be desirable. Where such electrodes are used in the practice of my invention they are to be regarded as falling within the scope thereof.

20 The stream of electrons emitted from the opening 7 is transmitted through an electrical resonator 11 which has the form of a hollow dumbbell. The resonator is so disposed that the electron stream passes through the center of the constricted portion 13 in a direction perpendicular to the longitudinal axis. The ends 15 of the dumbbell are not of spherical shape but are 25 preferably ellipsoids of revolution having a substantial eccentricity with the axes of revolution 30 perpendicular to the longitudinal axis of the dumbbell. The ends of the dumbbell may of course take other forms than ellipsoids of revolution. However, whatever form is selected, it is essential that the major axis of an end should 35 be substantially different than the minor axes in the plane perpendicular to the longitudinal axis of the dumbbell. Thus a parallelopiped, the base of which is a rectangle, is one possible form.

Because the ends of the dumbbell lack 40 spherical symmetry, the mode of electrical oscillation of the dumbbell in which the electric field is parallel to the direction of the stream is different from its mode of oscillation in which the electric field is perpendicular to the stream. The 45 frequency corresponding to the latter mode of oscillation is selected for use in the present connection, and the field produced when the resonator is excited to oscillate in this mode is impressed on the stream. The stream, accordingly, is laterally deflected as indicated by the diverging arrow lines 17 and 19 which represent 50 two of its positions. The deflection is periodic and its frequency is equal to the frequency corresponding to the selected mode of oscillation of the resonator.

To cause the resonator 11 to oscillate in a predetermined manner, the corresponding frequency must be impressed thereon. Where a system according to my invention is used for amplifying purposes, a potential corresponding to the frequency of the desired mode of oscillation is impressed from an external source. However, in general, my invention is used for the conversion of direct current energy into oscillatory energy, and in such a case a feed-back coupling from the emitter of the oscillating energy is provided. For the present, it may be assumed that resonator 11 is excited to oscillate at the proper frequency and impresses a periodic deflection on the electron stream.

After the stream leaves the resonator 11, it has a substantial component of velocity along its original direction in addition to the lateral periodic component. A second hollow body resonator 21 which is preferably in the form of a narrow box with the smaller dimension along the original direction of motion of the stream is disposed in the path of the stream and the stream enters the resonator through an elongated grid 23 in its incident surface.

The resonator 21 is so dimensioned that the first harmonic of its mode of oscillation for which the sense of the electric field is substantially parallel to the original direction of motion of the stream has a frequency equal to the frequency of excitation of the dumbbell resonator. The corresponding electric field distribution produced at any instant within the second resonator in such a case corresponds to the full-line sine curve 25 shown in the drawing within the resonator. In the upper region the electric field has one polarity, as indicated by an arrow labeled E and in the lower region, it has the opposite polarity as indicated by another arrow. The resonators 11 and 21 are so spaced and the electric fields at which they are excited to oscillate is so phased that the stream passes through the latter resonator 21 at any instant at the time when the electric field in the region in which it passes is such as to oppose the forward motion of the electrons. The field thus absorbs energy from the electrons while varying at the frequency corresponding to its lateral movement.

The energy derived from the electron stream is to a large extent radiated from an antenna 27 which passes through a hollow tube 29 extending from the resonator 21. In the region in which it is connected to the resonator 21, the antenna 27 is provided with a loop 31, the plane of which is such that the magnetic field corresponding to the electric field which derives energy from the electrons threads the area bounded by the loop. The loop 31 may be properly oriented by determining the direction of the magnetic field. In the structure illustrated in the drawing, the magnetic field lines are represented by the closed curvilinear arrows 33 which are illustrated as lying in the plane perpendicular to the electric field. The loop 31 is, therefore, oriented in a plane perpendicular to the plane of the arrows 33.

Where the system is to be used for producing oscillations, there is an interchange of energy between the energy deriving resonator 21 and the deflecting resonator 11. The transfer of energy takes place through a conductor 35 extending from a loop 37, properly oriented in the deflecting resonator 11 to a loop 39 properly oriented in the deriving resonator 21. The conductor is shielded by a conducting tube 41 interconnect-

ing the resonators. In the deflecting resonator 11, the position of the loop 37 may be determined by considering the direction of the magnetic field corresponding to the excited mode of oscillation of the resonator. The direction of the magnetic field at a series of points is represented by the curvilinear arrow 43 labeled "H" below the resonator 11. The plane of the loop 37 should be such that it is threaded by the magnetic field represented by the arrow 43. The loop in the deriving resonator 21 should be oriented to be threaded by the magnetic field represented by the arrows 33. For the purpose of adjusting the positions of the loops 31, 37 and 39 and timing the resonators 11 and 21, magnetically or thermally actuatable levers may be provided.

In the direction in which the resonators 11 and 21 are threaded by the stream of electrons, their dimensions should be so small that the proper deflection of the stream and the efficient derivation of energy is not impaired by the subjection of the electrons to the field for prolonged time intervals. These dimensions are determined by taking into consideration the selected frequency of oscillation of the resonators and the speed of the electrons. The time interval during which an electron of average velocity is present within the deflecting resonator 11 should be so short with reference to the period of oscillation of the resonator, that the electron as it passes from the inlet opening to the outlet opening of the resonator is subjected to a substantially constant electric field. In the case of the deriving resonator 21 it is also desirable that the electric field affecting any portion of the stream of electrons should be substantially constant. However, if this condition is not fully attainable, it is at least essential that the electrons should always move against the electric field in the region through which they are passing.

After the electrons pass through the absorbing resonator, they are deflected from a conducting plate 45 to the wall of the container 1 which is grounded. The building up of a stated charge in any region of the system is thus prevented.

The resonant wave length of a hollow body oscillator is comparable to its linear dimension corresponding to selected mode of oscillation. With a tube of a relatively small dimension incorporating relatively small resonators 11 and 21, powers of wave lengths of from several millimeters to several decimeters may, accordingly, be radiated. To improve the operation of the resonators, they may be filled with a low loss dielectric material such as rutile.

Although I have shown and described a certain specific embodiment of my invention, I am fully aware that many modifications thereof are possible. My invention, therefore, is not to be restricted except insofar as is necessitated by the prior art and by the spirit of the appended claims.

I claim as my invention:

1. A hollow body resonator comprising a dumbbell shaped bell, the end portions of which have major axes in a plane perpendicular to the longitudinal axis of the shell, said axes being of substantially different length.
2. A generator, detector or amplifier of electrical oscillations comprising a conducting shell constituting an electromagnetic resonator, means for projecting a stream of electrical charges through said shell, said shell being so oriented with respect to the line of said charges that the electrical field corresponding to one mode of oscillation of said shell imposes on said stream a periodic lateral de-

fection corresponding to said mode of oscillation, and another shell, constituting an electromagnetic resonator having a mode of oscillation of a frequency substantially equal to that of said one mode mounted to receive said charges after said stream has been deflected, said last named shell being so oriented that the electrical field corresponding to said mode of oscillation of said last named shell is parallel to said stream and is manifested as a standing wave extending between the terminal points between which said stream oscillates laterally and having a nodal point intermediate of said terminal points, the polarities of the fields at different points of said standing wave being such as to oppose the motion of the charges in said stream.

3. A generator of electrical oscillations comprising a conducting shell constituting an electromagnetic resonator, means for projecting a stream of electrical charges through said shell, said shell being so oriented with respect to the line of said charges that the electrical field corresponding to one mode of oscillation of said shell imposes on said stream a periodic lateral deflection corresponding to said mode of oscillation, another shell constituting an electromagnetic resonator and having a mode of oscillation of a frequency substantially equal to that of said one mode disposed to receive said charges after said stream has been deflected, said last-named shell being so disposed that the electrical field corresponding to said mode of oscillation of said last named shell is parallel to said stream and is manifested as a standing wave extending between the terminal points between which said stream oscillates laterally and having a nodal point intermediate of said terminal points, the polarities of the fields at different points of said standing wave being such as to oppose the motion of the charges in said stream, and means for coupling said shells so that there is an interchange of energy between them.

4. A generator of electrical oscillations comprising a conducting shell constituting an electromagnetic resonator, means for projecting a stream of electrical charges through said shell, said shell being so oriented with respect to the line of said charges that the electrical field corresponding to one mode of oscillation of said shell imposes on said stream a periodic lateral deflection corresponding to said mode of oscillation, and another shell constituting an electromagnetic resonator and having a mode of oscillation of a frequency substantially equal to that of said one mode disposed to receive said charges after said stream has been deflected, said last-named shell being so disposed that the electrical field corresponding to said mode of oscillation of said last-named shell is parallel to said stream and is manifested as a standing wave extending between the terminal points between which said stream oscillates laterally and having a nodal point intermediate of said terminal points, the polarities of the fields at different points of said standing wave being such as to oppose the motion of the charges in said stream, said shells being so dimensioned in the region in which they are penetrated by said stream with reference to the velocity of said stream that the charges of said stream reacts with an electrical field which is substantially constant for all practical purposes during the time that said charges are subjected to said field.

5. Apparatus for generating electrical oscillations comprising means for projecting a stream of

electrical charges, means for swinging said stream laterally at the periodicity of said oscillations, and means for producing a periodic electromagnetic field having the periodicity of said oscillations in the path of said stream, the electric vector of said field being substantially along the line of said stream and having a polarity opposite to that of said stream in the region in which said stream impinges on said field at any instant and having the opposite polarity at the same instant in a contiguous region.

5 6. In combination, a conducting shell constituting an electromagnetic resonator and having two end portions and a constricted portion joining said two end portions, means for passing a stream of electrons through said constricted portion of said shell only, said shell being so shaped that the electric field corresponding to one mode of oscillation of the shell is at substantially right angles to said stream, and means for producing oscillations in said shell in said one mode whereby a periodic lateral deflection of said stream is effected.

15 7. In combination, a conducting shell constituting an electromagnetic resonator and having a constricted portion, means for passing a stream of electrons through said constricted portion of said shell only, said shell being so shaped that the electric field corresponding to one mode of 20 oscillation of the shell is at substantially right angles to said stream, means for producing oscillations in said shell in said one mode whereby a periodic lateral deflection of said stream is effected, and means for producing a periodic electromagnetic field having the periodicity of said 25 oscillations in the path of said stream after it has passed through said shell, the electric vector of said field being substantially along the line of said stream and having a polarity opposite to that of 30 said stream in the region in which said stream impinges on said field at any instant and having the opposite polarity at the same instant in a contiguous region.

35 8. In combination, a conducting shell constituting an electromagnetic resonator and having a constricted portion, means for passing a stream of electrons through said constricted portion of said shell only, said shell being so shaped that the electric field corresponding to one mode of 40 oscillation of the shell is at substantially right angles to said stream, means for producing oscillations in said shell in said one mode whereby a periodic lateral deflection of said stream is effected, and another shell constituting an electromagnetic res-

50 onator having a corresponding mode of oscillation of a frequency substantially equal to that of said one mode mounted to receive said stream of electrons after deflection thereof, said last named shell being so oriented that the electrical field of 55 said corresponding mode of oscillation is parallel to said stream and is manifested as a standing wave extending between the terminal points between which said stream oscillates laterally and having a nodal point intermediate of said terminal points, the polarities of the fields at different points of said standing wave being such as to 60 oppose the motion of the electrons in said stream.

65 9. The combination of a hollow body resonator comprising a dumb-bell shaped shell having a constricted center portion and a pair of end portions, the end portions having major axes in a plane perpendicular to the longitudinal axis of the shell, said axes being of substantially different length, means for projecting a stream of electrical charges through said constricted center portion

in a direction perpendicular to the electric field corresponding to one of the modes of oscillation of said shell, and means for producing oscillations in said shell in said one mode whereby a periodic lateral deflection of said stream is effected.

10. The combination of a hollow body resonator comprising a dumb-bell shaped shell having a constricted center portion and a pair of end portions, the end portions having major axes in a plane perpendicular to the longitudinal axis of the shell, said axes being of substantially different length, means for projecting a stream of electrical charges through said constricted center portion in a direction perpendicular to the elec- 10 16

tric field corresponding to one of the modes of oscillation of said shell, means for producing oscillations in said shell in said one mode whereby a periodic lateral deflection of said stream is effected, and means for producing a periodic electromagnetic field having the periodicity of said oscillations in the path of said stream after it has passed through said shell, the electric vector of said field being substantially along the line of said stream and having a polarity opposite to that of said stream in the region in which said stream impinges on said field at any instant and having the opposite polarity at the same instant in a contiguous region.

EDWARD U. CONDON.
